CLAIM

The ornamental design for a construction set element, as shown and described.

DESCRIPTION

FIG. 1 is a top perspective view of a construction set element showing the new design;

FIG. 2 is a bottom perspective view of the construction set element of FIG. 1;

FIG. 3 is a top plan view of the construction set element of FIG. 1;

FIG. 4 is a bottom plan view of the construction set element of FIG. 1.

FIG. 5 is a front elevational view of the construction set element of FIG. 1;

FIG. 6 is a rear elevational view of the construction set element of FIG. 1;

FIG. 7 is a right side elevational view of the construction set element of FIG. 1; and,

FIG. 8 is a left side elevational view of the construction set element of FIG. 1.

The dash-dot broken lines represent the bounds of the claim and all other broken lines represent unclaimed portions of the construction set element. The dash-dot boundaries indicate the appearance of any portion of the article between the boundaries forms no part of the claimed design. None of the broken lines or unshaded areas form a part of the claimed design.

1 Claim, 8 Drawing Sheets
